UNITED STATES PATENT OFFICE.

LEOPOLD SIMON, OF NEW YORK, N. Y.

WINDOW-SCREEN.

1,386,033.

Specification of Letters Patent.

Patented Aug. 2, 1921.

Application filed July 8, 1915. Serial No. 38,637.

To all whom it may concern:

Be it known that I, LEOPOLD SIMON, a citizen of the United States, residing at New York, in the county of New York and 5 State of New York, have invented certain new and useful Improvements in Window-Screens, of which the following is a full, clear, and exact description, such as will enable others skilled in the art to which it 10 appertains to make and use the same.

This invention relates to screens, and with respect to certain more specific features thereof, to adjustable and foldable light and air deflectors for window, porch and other 15 building purposes.

One of the objects of the invention is to provide a device of the above character which is capable of easy manipulation and is reliable and efficient in operation.

20 A further object is to provide an improved screen adapted to control effectively the passage of light or air therethrough, as desired.

A further object is to provide a weather shield of the above character which includes 25 various features of structural superiority and functional advantage.

Other objects and advantages will be in 30 part obvious and in part noted hereinafter in connection with the following description of the accompanying drawings, which illustrate a typical embodiment of the invention.

The invention accordingly consists in the features of construction, combinations of elements and arrangement of parts which will 35 be exemplified in the construction herein-after set forth, and the scope of the application of which will be indicated in the following claims.

In the drawings,

40 Figure 1 represents a screen applied to a window opening;

Fig. 2 is a vertical sectional view thereof;

Fig. 3 is a perspective view of a part;

45 Fig. 4 is a sectional detail of a screen strip and clamp;

Fig. 5 is an isometric view of a rod support; and

Fig. 6 is a sectional view of a locking device.

50 Referring more particularly to the drawings, there is indicated a window casing having upright sides 1 and a transverse top 2, adjacent the corners of which are secured a pair of supporting brackets 3. A guiding support 4, preferably in the form of a square rod or bar with round extremities,

is journaled to rotate freely in the brackets 3. A pair of screen-carrying devices are suspended from the rod 4 and are provided with a plurality of flexible or collapsible 60 screens or screen strips 5 extending therebetween. These devices or frames preferably comprise transversely mounted angle members or cross pieces 6 and 7 arranged at opposite ends of the rod 4 and having a 65 pair of vertically disposed parallel links 8 pivotally connected to their ends. Additional cross members 9 are pivotally connected between the links of each frame for attaching the screens and for insuring a 70 parallel transverse and opposite simultaneous movement thereof when the rod 4 is rotated. The angle member 7 is preferably fixed to the bar 4 adjacent one side of the window casing 1, while the other angle member 6 is secured to a sleeve member or 75 bracket 11 having a square bearing aperture for the rod 4. The sleeve 11 is thus mounted for translatory movement on the support 4 toward and away from the other frame for 80 collapsing or extending the flexible screens therebetween. In order to render the sliding movement of the sleeve 11 free, ball bearings 12 are seated in the sleeve to ride on the support.

85 Locking means are preferably provided to hold the sleeve 11 in either extended or retracted position and thus maintain the screen strips taut or securely folded. As illustrated, the locking means for the first men- 90 tioned purpose comprises a latch 13, pivoted to one end of a bell crank lever 14, which is in turn pivoted at 15 to the sleeve 11. A second and oppositely disposed bell crank lever 14^a is also provided to operate the 95 latch 13 for withdrawing the same from a recess 18 in the left end of shaft, its position for holding the screen folded. A coil spring 16 located in a recess 16' in an offset lug of one bell crank lever works against a plunger 17 in said recess and bears on the sleeve 11 to urge the latch 13 to locking position, that is, toward one of two recesses 18 provided in the support 4 adjacent its ends. An operating cord 19 is secured to the lever 14^a 100 at 20 and runs in a pulley 21, whereby the latch 13 may be released without translation of the screen frame and the translatable screen frame thereafter moved to extend the screen strips. A similar operating cord 22 105 is provided to move the sleeve 11 to the left for collapsing the screen, this cord, how-

ever, being attached to the free end of the bell crank lever 14 and running over a pulley 23, so that, on manipulation of the said cord, the latch 13 is withdrawn from locking position and the translatable frame then moved.

A folding device or brace 24 is provided longitudinally between the frames 8, 8, preferably adjacent their lower ends or other 10 point remote from the support 4, for rigidly spacing the frames when separated. In practice, this brace comprises a loosely articulated member, as two arms pivoted at their ends to cross channel irons connecting 15 the parallel links of the screen frames and jointed centrally at an elbow 25. A manually operable bolt 26 is seated in one of the arms of the brace and may be extended into the other when the brace is straightened for 20 locking the same. A take-up cord 27 is suspended from a central window bracket 28 and is threaded through the screens, as by extending down through apertures provided therefor in the screen strips, the same 25 being knotted below a pivotal eye 29 on the brace adjacent the elbow thereof. A suitable pendent weight 30 is carried by the cord 27 for normally straightening the latter. The offset forked arm of the sliding sleeve 30 or bracket 11, above mentioned, is provided with a roller 31 which travels in a path to intercept the take-up cord 27 so that, as the translatable frame is pulled to the left, after the brace is manually broken, the roller 31 35 engages the cord and carries the same therewith to fold the brace and screen strips upwardly between the side frames.

There are also provided brackets 32 on the sides of the window casing having studs 40 or pivot members 33 which take into central openings in certain of the cross members 9 of the frames and afford a rigid axis in addition to the support 4 about which the screen strips may be rotatably adjusted by 45 suitable means, such as a handle 34. To prevent displacement of the screen when the same is operated to folded position, a guide wire or rod 35 is provided at the lower end of the window and a pivoted central eye 36 50 on the lowest cross iron 9 serves to hook the translatable screen thereto. The rod 35 thus holds the screen against swinging when extended or collapsed.

In certain installations of the device, particularly with a screen of relatively great 55 length, *e. g.*, more than six feet, it is desirable to provide an intermediate supporting means, brace or carrier for the rod or bar 4 to prevent the same from sagging. 60 For this purpose, a bracket 37 is secured to the top of the window casing 2, and is provided with a depending shaft 38 which has journaled thereon a plurality, in the present instance four, of horizontally disposed and 65 equidistantly spaced arms or levers 39, 40,

41 and 42. These arms are curved downward slightly and one of the same is normally turned at right angles to the rod 4 to engage the lower surface thereof and support the same. As will be apparent, this arm extends in the path of movement of the translatable screen frame, but as said arms are free to rotate, the same will be turned through 90° by the right frame link 8 as the latter travels to the left. Accordingly, the 70 adjacent arm 39 will move under and support the rod 4 as the arm 42 leaves the same. Similarly, reverse movement of the translatable frame, when extending the screen, rotates the arms in an opposite direction, thus 75 allowing the sleeve 11 to travel to the right and returning the arm 42 beneath the rod 4. The bracket 37 is illustrated as provided with four arms since the screen is preferably 80 divided into sections, when the same is relatively long, and in such instances four or more screen frames and sliding sleeves may 85 successively pass and rotate the arms 39, 42.

As illustrated in Figs. 2 and 3, the pivotally movable screen strips 5 are superposed 9 in parallel planes and each comprises a flat longitudinal body portion 5^a and longitudinal or axially disposed edge portions 5^b and 5^c reversely inclined with respect to the body portion and transversely of the axes of rotation. The screens are mounted substantially equidistantly apart with axes in vertical alinement so that, as the same are turned to approach an approximately vertical plane, the down-turned edge 5^b of each 1 screen is overlapped by the opposite upturned longitudinal edge 5^c of the screen strip immediately therebelow. An effective and close nesting of the screen units is thus effected so that light and air may be substantially excluded from passage therethrough. Furthermore, the contour of the screen units serves to materially prevent the entrance of rain or snow through the screen, even when the same are adjusted to admit a free current of air.

In order that the screen units may be readily assembled or withdrawn from the other parts of the device when desired, end members, or clamps 43 are provided therefor, consisting of flexible metal strips reflexed over the ends of the screen strips and then doubled to provide curved or exteriorly V-shaped members laterally insertible in the holders 9, which also constitute cross members for the links 8 and are bent to provide longitudinally extending transversely curved open channels 9^a having a wall or web 9^b lying within the channel and projecting partway thereacross to lie in the recess, or concavity, in the U-shaped member. The screen clamps may thus be readily telescoped laterally to nest within the holders, the clamps being preferably longer than the holders, so that the ends of the former ex-

tend without the latter, as indicated in Fig. 2. After assembly these projecting ends are inclined or offset, as indicated, for the purpose of inclining the edges of the screen member 5, as above set forth, and also for locking the screen members against unintentional displacement.

While the operation of the device will be largely obvious from the foregoing description of the structure, the same may be briefly set forth as follows: Assuming the screen to be in extended operative position, as illustrated in Fig. 1, the same may be folded or collapsed by manual release of the brace lock 26 and operation of the cord 22. The latter serves to automatically release the sleeve latch 13 and thereafter slide the sleeve 11 and the right frame members to the left, thereby collapsing the screens. When the bracket 11 reaches mid-position on the support 4, the roller 31 picks up the brace cord 27 and the latter, with the brace 24, takes up the slack in the screen strips thus successively looping the strips and renders the whole device compact and firm when folded. Thereafter, manipulation of the opposite cord 19 releases latch 13 and moves the translatable frame to the right, whereupon the sleeve 11 will be locked in extended position and the brace simultaneously straightened to rigidly longitudinally space the lower ends of the links 8. In the operation of extending the screen, the right frame will fit over the pivotal stud 33 provided on the right window casing. It will be understood that the arms 39, 40, 41, and 42 operate in the manner above described to support the rod 4 and thereby prevent sagging or bending.

In certain installations it is also desirable to provide one or more metal strips 44 secured longitudinally to certain of the links 8. These strips serve to close any gap between the sides of the screen and the window frame, and also to reinforce the links. Furthermore, when a plurality of the screens are provided to operate in opposite directions on a single support 4, the metal strips 44 overlap when the screens are extended and thereby prevent any objectionable openings between the screens when closed.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the in-

vention which, as a matter of language, might be said to fall therebetween.

Having described my invention, what I claim as new and desire to secure by Letters Patent, is:—

1. In a device of the character described, in combination, a support, a plurality of frames, one of which is translatable on said support toward and from the other and comprises a plurality of parallel links movable relatively to each other transversely of said support, a flexible screen supported by and between said frames, means to move said translatable frame, and means controlled by said first-mentioned means to lock and release said frame.

2. In a device of the character described, in combination, a guiding support, a plurality of screen-carrying frames, including one translatable on said support relatively to the other, and a foldable brace between said frames to rigidly space the same when separated.

3. In a device of the character described, in combination, a transverse support, a plurality of screen-carrying frames, including one translatable on said support, a foldable brace between said frames to rigidly space the same when separated, and means to lock said foldable brace in a predetermined position.

4. In a device of the character described, in combination, a transverse support, a plurality of screen-carrying frames thereon, one being movable relatively to the other, a plurality of flexible screens extended between said frames, and a foldable brace between said frames to rigidly space the same when separated and to take up slack in said screens when said movable frame approaches the other.

5. In a device of the character described, in combination, a support, a plurality of screen-carrying frames, including one translatable on said support relatively to the other and comprising a plurality of parallel links movable relatively to each other transversely of said support, a flexible screen supported by and between said frames, and a foldable brace between said frames to rigidly space the same when separated.

6. In a device of the character described, in combination, a transverse support, a plurality of screen-carrying frames, including one translatable on said support, a plurality of flexible screens extended between said frames, a foldable brace between said frames having its ends pivoted to the latter remote from said support and having a medial elbow, and a take-up cord for said foldable brace secured to the same adjacent said elbow.

7. In a device of the character described, in combination, a support, a plurality of screen-carrying frames, including one trans-

- latable on said support relatively to the other and comprising a plurality of parallel links movable relatively to each other transversely of said support, a flexible screen
- 5 strip extending between said frames, and attaching means for the ends of said strip serving to incline oppositely the longitudinal edges thereof with respect to the body portion thereof.
- 10 8. In a device of the character described, in combination, spaced parallel frame members, a plurality of flexible screen strips extended therebetween, and attaching means for the ends of said strips serving to incline oppositely the longitudinal edges thereof with respect to the body portions thereof.
- 15 9. In a device of the character described, in combination, a transverse support, a plurality of screen carrying devices thereon, including one translatable toward and from the other and comprising a plurality of vertically disposed parallel links movable relatively to each other transversely of said support and a translatable sleeve carrying
- 20 25 said links, means to move said translatable device, means controlled by said first-mentioned means to lock and release said translatable device, a plurality of flexible screen strips extending between said devices, attaching means for the ends of said strips serving to incline oppositely the longitudinal edges thereof with respect to the body portions thereof, and a brace between said first-mentioned devices to rigidly space the same
- 30 35 when separated.
10. In a device of the character described, in combination, a plurality of sets of holders arranged in pairs, each of said pairs being pivoted about a common axis and the axes of the pairs being parallel, the holders of each pair having parallel channels, and a plurality of flexible screen strips each having end members adapted to be retained in the channels of the successive pairs of
- 40 45 holders.
11. In a device of the character described, in combination, a screen holder having a longitudinal curved channel and a screen clamp having a body portion fitting in said channel, said holder and said clamp being bent transverse to the axis of the channel to retain said clamp in said holder.
12. In a device of the character described, in combination, a screen holder having a longitudinal curved channel and a screen clamp having a body portion fitting in said channel, said holder and said clamp being bent transverse to the axis of the channel at each end of the holder, one end of the holder being bent in a direction opposite to that of the other.
13. In a device of the character described, in combination, a transverse guiding support, and a plurality of vertically disposed
- 50 55 60 65 screen - carrying frames depended there-
- from, one of said frames being translatable relatively to the other and including a sleeve having an anti-friction bearing on said support.
14. In a device of the character described, in combination, a sliding and locking member having oppositely disposed bell-crank levers pivoted thereon, a latch operable by said levers, and manipulative cords to actuate said levers. 75
15. In a device of the character described, in combination, a transverse rod supported at its ends, a screen-carrying device translatable on said rod, and means to support said rod intermediate its ends while permitting free translatory movement of said device. 80
16. In a device of the character described, in combination, a transverse rod and an intermediate support therefor comprising a horizontally disposed swinging arm normally underlying said rod and movable in opposite directions to disengage the same. 85
17. In a device of the character described, in combination, a screen-holding bar having a longitudinal channel open at one end for the reception of a screen clamping member, said bar having a web within said channel and projecting partway across said channel, and a screen clamping member adapted to fit said channel and having a recess for the reception of said web. 90
18. In a device of the character described, in combination, a screen-holding bar having a longitudinal channel open at one end for the reception of a screen clamping member, said bar having a web within said channel and projecting partway across said channel, and an exteriorly U-shaped screen clamping member adapted to fit said channel the said web being received in the concavity of the U-shaped clamping member. 100
19. In a device of the character described, in combination, a pair of frames, one movable toward the other, collapsible screens supported between said frames and a foldable brace adapted to maintain the frames apart from each other. 110
20. In a device of the character described, in combination, a pair of frames, one movable toward the other, collapsible screens supported between said frames, a latch movable with the movable frame, and a cord to operate said latch, said cord being connected to move said movable frame. 115
21. In a device of the character described, in combination, a pair of frames, one movable toward the other, a plurality of collapsible screens supported between said frames for simultaneous rotative movement on parallel axes, the axially disposed edges of said screens being inclined transversely of said axes. 125
22. In a device of the character described, in combination, a pair of frames, one mov-

- able toward the other, collapsible screens supported between said frames, a bar adapted to guide and support said movable frame, and bar supporting means including movable bar supporting members, adapted one to be moved into and another out of bar supporting position by movement of said movable frame past said bar supporting means. 5
23. In a device of the character described, in combination, a pair of frames, one movable toward the other, collapsible screens supported by and between said frames and a loosely articulated screen looping member. 10
24. In a device of the character described, in combination, a pair of frames, one movable toward the other, collapsible screens supported between said frames and a screen take up cord operable by movement of said movable frame. 15
25. In a device of the character described, in combination, a pair of frames, one movable toward the other, collapsible screens supported between said frames, a foldable brace adapted to hold said frames apart, a latch movable with the movable frame, and a cord to operate the latch, said cord being connected to move the movable frame. 20
26. In a device of the character described, in combination, a pair of frames, one movable toward the other, a plurality of collapsible screens supported between said frames for simultaneous rotatable movement on parallel axes, the axially disposed edges of said screens being inclined transversely of said axes, a foldable brace adapted to hold said frames apart, a latch movable with the movable frame, and a cord to operate the latch, said cord being connected to move the movable frame. 25
27. In a device of the character described, in combination, a pair of frames, one movable toward the other, collapsible screens supported between said frames, a foldable brace adapted to hold said frames apart, a latch movable with the movable frame, a cord to operate the latch, said cord being connected to move the movable frame, a bar adapted to guide and support said movable frame, and movable bar supporting members adapted one to be moved into and another out of bar supporting position by movement of said movable frame past said supporting means. 30
28. In a device of the character described, in combination, a pair of frames, one movable toward the other, collapsible screens supported between said frames, a foldable brace adapted to hold said frames apart, said brace being disposed to successively loop the intermediate portion of said screens as said frames approach each other. 35
29. In a device of the character described, in combination, a pair of frames, one movable toward the other, collapsible screens supported between said frames, a foldable
- brace adapted to hold said frames apart, said brace being disposed to successively loop the intermediate portion of said screens as said frames approach each other, and a screen take up cord in the path of said movable frame. 70
30. In a device of the character described, in combination, a pair of frames one movable toward the other, each of said frames including a cross piece, parallel links pivoted to said cross pieces and screen holders pivoted to the links, screens between said frames connected to said holders, a bar along which one of said frames is movable toward and from the other, a foldable brace pivotally connected to said frames, a take up cord threaded through said screens, and disposed in the path of said movable frame. 75
31. In a device of the character described, in combination, a pair of frames one movable toward the other, each of said frames including a cross piece, parallel links pivoted to said cross pieces and screen holders pivoted to the links, screens between said frames connected to said holders, a bar along which one of said frames is movable toward and from the other, a foldable brace pivotally connected to said frames, a take up cord threaded through said screens, and disposed in the path of said movable frame. 80
32. In a device of the character described, in combination, a pair of frames one movable toward the other, each of said frames including a cross piece, parallel links pivoted to said cross pieces and screen holders pivoted to the links, screens between said frames connected to said holders, a bar along which one of said frames is movable toward and from the other, a foldable brace pivotally connected to said frames, a take up cord threaded through said screens, and disposed in the path of said movable frame. 85
33. In a device of the character described, in combination, a pair of frames one movable toward the other, each of said frames including a cross piece, parallel links pivoted to said cross pieces, screen holders pivoted to the links, screens between said frames connected to said holders, and a stationary pivot member adapted to be engaged by a cross piece pivotally joining said links when the screens are extended. 90
- In testimony whereof I affix my signature, in the presence of two witnesses.

LEOPOLD SIMON.
